UNITED STATES PATENT OFFICE.

FRANCIS J. CARMAN, OF WASHINGTON, DISTRICT OF COLUMBIA.

PROCESS OF REFINING SULPHUROUS PETROLEUM.

SPECIFICATION forming part of Letters Patent No. 501,988, dated July 25, 1893.

Application filed May 19, 1893. Serial No. 474,771. (No specimens.)

To all whom it may concern:

Be it known that I, FRANCIS J. CARMAN, a citizen of the United States, at present residing in the city of Washington, District of Columbia, have invented a new and useful Process for the Refining of Sulphurous Petroleum, and of which the following is a specification.

Sulphurous petroleum is the term applied to that class of natural oils which contain appreciable quantities of sulphur and other deleterious impurities, whose presence imparts an offensive odor to the oil and its products, or which develop an odor during combustion, and incrust the lamp chimney with the products of combustion.

The methods hitherto in use for the desulphurizing of mineral oils have been many and various. One method consists in agitating the distillates with chemicals, generally plumbate of soda, whereby certain sulphur compounds will yield their sulphur, with formation and precipitation of sulphide of lead, and the removal of the excess of plumbate by a second agitation with flowers of sulphur. It has been found, that, inasmuch as the oils contain sulphur in some forms of combination which will not yield to the plumbate, the sulphur is not wholly eliminated; traces of lead oxide also remain dissolved in the oil, thereby impairing its burning qualities.

Another method is the distillation of the crude oil or of a distillate therefrom, with metallic oxides, which may retain the sulphur in combination or may cause it to pass off in the form of sulphurous acid gas, or both. The disadvantages of this process are: first, the necessity of agitating the oxides in the oil; second, the labor and expense incidental to revivifying the spent oxides.

Another method consists in distilling the crude oil or its distillates, and removing the sulphur from the vapor before condensation; one method in this class, is to pass the vapor over a surface of solid metallic particles, or of metallic oxides, which are kept superheated in order to prevent condensation of the vapor undergoing treatment. The desulphurizing agent is afterward removed from its chamber and suitably roasted or otherwise renovated. The objections to this method are: first, that it involves considerable handling and ma-

nipulation of the desulphurizing agent; second, that as the chemical action is by contact, the only available portion of the agent is its surface, and the use of solid fragments therefore necessitates a large excess of such agent over the amount theoretically necessary; third, the difficulty of maintaining the necessary temperature throughout the mass of fragments which necessitates excessive firing upon the outside of the desulphurizing chamber, which is destructive to masonry and wasteful of fuel.

An examination of the various processes for desulphurizing oil, and an intimate knowledge of sulphurous oil refining, will show that any process of this nature, in order to be eminently efficient and economical, must employ an agent of such nature and under such conditions that it will, first, so react upon the sulphur compounds as to reduce them to the same form of combination; second, which will at the same time readily combine with the sulphur while in that form of combination; third, which will not be hampered by an inert accumulation or crust of the resultant compound; fourth, which owing to its nature and condition, is easily capable of being kept at the proper temperature with a small expenditure of fuel; fifth, which is capable of revivification with little or no loss of substance or of oil, with the least amount of labor, and also without being removed from its receptacle. The process of spraying the vapor through or over a mass of molten metallic lead, I find to answer each and all of these requirements.

My invention therefore consists, first, in passing the oil vapors containing sulphur compounds, over or into a mass of molten metal capable of combining with the sulphur of said compounds, and also of retaining in solution the combinations so formed; secondly, in passing the oil vapors over or into a mass of melted lead or an alloy of the same, producing lead sulphide, which dissolves in the molten mass; thirdly, in desulphurizing the oil and revivifying the agent without removing the same from its receptacle; fourthly, in revivifying the mass of lead by means of a current of air, and finally in desulphurizing the vapor and simultaneously revivifying the desulphurizing agent.

My invention consists also in certain details hereinafter described and pointed out in the claims.

Owing to the temperature of the molten lead, the chemical action is very energetic, the sulphur compounds being reduced by the lead with formation of sulphide of lead, and owing to the ready solubility of this compound in molten lead it is dissolved as fast as formed and the lead is continually free to act unhampered by any inert crust.

In order to renew the lead when it becomes saturated or when the amount of sulphur therein becomes so great as to interfere with the successful working of the process, a suitable oxidizing agent is introduced, which oxidizes the sulphur to sulphurous acid gas, partly by direct action, and partly by forming litharge, which reacting in turn, oxidizes the sulphur with formation of sulphurous acid gas and reduction of the litharge to metallic lead. The cheapest and most convenient method of thus roasting off the sulphur, is to blow air through the molten mass until sulphurous gas ceases to escape. Any excess of air will form litharge, which will be easily reduced by the first oil vapor of the next run.

I do not confine myself strictly to the use of lead in this process, as alloys of this metal may be used.

In order to render the lead more easily fusible, other metals, notably arsenic, may be introduced in varying quantities. Zinc, tin, mercury, or antimony or their alloys may also be used, but owing to the simplicity of the action when using lead or an alloy in which lead predominates, it is judged best to use the lead alone or with little foreign alloy.

The drawings hereunto annexed show an apparatus by means of which my process may be carried out, but other forms may be used, and in fact, its structure will depend very largely upon the rest of the refinery.

In carrying out my process, the oil to be desulphurized is distilled in a suitable apparatus, the vapors are conducted by a suitable pipe A, into the desulphurizing chamber B, where, as heretofore described, the sulphur is retained, and the vapors are allowed to pass on to a condenser through the pipe C. According to my process, I partially fill the receptacle with a mass of molten metal K, and keep the mass in a molten state during the entire operation. In practice, I have used a mass of molten lead, but an alloy of that metal will answer, so that my invention comprehends all alloys of lead as well as the pure metal. The oil vapors upon entering the desulphurizing chamber, may be forced down

into the molten mass by means of a perforated pipe D leading thereto, or they may be sprayed or impinged upon the surface of the molten metal, the chemical action being the same in both cases. When it is wished to renew or revivify the lead, the sulphur therein is roasted off as heretofore described. The air is forced into the mass through the pipe E, and the surplus air carrying off the sulphurous gas escapes through H. The lead is thus ready for use again without having been removed from the chamber. The vapor and the air outlets are each provided with cocks I, enabling the air conduits to be closed during the desulphurizing of the vapors, and the vapor conduits to be closed during the desulphurizing of the lead. It is possible, however, to accomplish desulphurization of the vapor and of the lead simultaneously. This I do by introducing into the lead a stream of air so regulated in amount that the sulphur is oxidized as rapidly as it is absorbed by the lead, and passes off with the vapor as sulphurous acid gas, which does not react upon the hydrocarbon vapor. The pipe H will of course be closed during this operation.

Having thus described my invention, what I claim is—

1. The process herein described for desulphurizing oils which consists in passing the oil vapors through a receptacle containing a mass of melted metal, which will reduce the sulphurous vapors to a common form of combination, and then combine with the sulphur.

2. The process herein described for desulphurizing oils, which consists in passing the oil vapor into contact with a mass of melted metal, of which lead is the essential element.

3. The process herein described for desulphurizing oils which consists in passing the oil vapor into contact with a mass of melted lead, whereby the sulphide of lead is formed and immediately dissolved, as described.

4. The process herein described for desulphurizing oils, which consists in passing the oil vapors into contact with a mass of melted metal, and subsequently desulphurizing the melted mass by means of an oxidizing agent, substantially as shown and described.

5. The process herein described for desulphurizing oils which consists in passing the oil vapors into contact with a mass of melted lead, and revivifying said lead by means of a current of air brought into contact therewith, substantially as set forth.

FRANCIS J. CARMAN.
